SHIELD FOR SWITCHGEAR ENCLOSURES

Glen L. Claybourn, Pittsburgh, and Gordon G. Gernhardt, Swissvale, Pa., assignors to Westinghouse Electric Corporation, East Pittsburgh, Pa., a corporation of Pennsylvania

Application August 22, 1946, Serial No. 692,398

7 Claims. (Cl. 160—77)

1

Our invention relates, generally, to switchgear, and, more particularly, to metal enclosed switchgear of the outdoor type.

In order to permit maintenance, renewal of recording instrument charts and relay adjustments on outdoor switchgear during inclement weather, it is desirable to provide some protection for both the operating personnel and the apparatus.

An object of our invention is to provide a detachable frame for supporting a removable cover for the doorway of an enclosed outdoor switchgear housing.

Another object of our invention is to provide a detachable framework which is self-locking in position on a switchgear housing.

A more general object of our invention is to provide a detachable framework which is simple and efficient in operation and which may be economically manufactured and installed.

Other objects of our invention will be explained fully hereinafter or will be apparent to those skilled in the art.

In accordance with one embodiment of our invention, the framework for a removable covering for the doorway of an outdoor switchgear housing is so constructed that the framework locks itself in position above the doorway. The framework may be removed by first swinging it through a small angle and then withdrawing it from the door jamb.

For a better understanding of the nature and objects of our invention, reference may be had to the following detailed description, taken in conjunction with the accompanying drawing, in which:

Figure 1 is a view, in side elevation, of an outdoor switchgear housing with a removable covering framework constructed in accordance with our invention;

Fig. 2 is an enlarged view, in plan, of the removable framework;

Fig. 3 is an enlarged view, in side elevation, of the framework;

Fig. 4 is a detail view, partially in elevation and partially in section, showing the frame locked in position on the door jam of the housing;

Fig. 5 is a detail view of the locking device, and

Fig. 6 is an enlarged view, taken along the line VI—VI in Fig. 1.

Referring to the drawing, particularly to Fig. 1, the structure shown therein comprises a switchgear housing 10 which may be of the type

2

commonly known as an outdoor switchhouse, and a removable canopy or shield 11 for protection during inclement weather. The canopy 11 comprises a detachable framework which may be covered in different ways, such as by placing over the framework a tie-down throwover canvas, or by making a formed canvass enclosure of top, front and two sides which can be snap-fastened to the removable framework. If desired, a folding sheet metal covering may be provided for the framework.

As shown most clearly in Figs. 1 and 2, the framework of the canopy 11 comprises a U-shaped member 12 having a cross member 13 secured to the ends of its legs and a brace comprising members 14 and 14' secured on the bottom side of each leg. The members of the framework may be secured together by welding, or other suitable means.

In order to retain the framework securely in position and make it quickly attachable and detachable, two or more self-locking devices 15 are provided. As shown in Fig. 5, each locking device 15 comprises a flat piece of metal 16 having one edge welded to the cross member 13, a U-shaped piece 17 having one leg welded to the bottom of the flat piece 16 and a round bar 18 welded to the bottom of the U-shaped piece 17 adjacent to the other leg.

As shown in Fig. 4, the top supporting bar 13 slides into a horizontal well or recess 19 formed by a U-shaped portion 19' in a door jamb 21 on the housing 10. When the framework is swung downwardly the round bar 18 is so disposed behind the door jamb 21 that the framework is locked in position. As shown in Fig. 1, the vertical portions 14 of the brace members are disposed in vertical wells or recesses 22 in the sides of the door jamb 21 when the framework of the canopy is in position on the housing. In this manner the framework is securely locked in position.

The framework may be removed by first swinging it upwardly about the cross member 13 to rotate the cross member, thereby lowering the bar 18 below the bottom lip of the well 19 and then withdrawing the framework forwardly away from the door jamb.

From the foregoing description, it is apparent that we have provided a removable canopy having a framework which may be quickly attached to and detached from a switchgear or similar housing. The framework is securely held in position by a self-locking device.

Since numerous changes may be made in the

above-described construction and different embodiments of the invention may be made without departing from the spirit and scope thereof, it is intended that all matter contained in the foregoing description or shown in the accompanying drawing, shall be interpreted as illustrative and not in a limiting sense.

We claim as our invention:

1. In a switchgear housing structure, in combination, a door jamb on the housing, said door jamb having a horizontally disposed U-shaped portion forming a well therein, a detachable framework, and self-locking means secured to the framework and cooperating with the bottom of the U-shaped portion to retain the framework in said well when the framework is swung downwardly about said well, said locking means being released by swinging the framework upwardly about said well.

2. In a switchgear housing structure, in combination, a door jamb on the housing, said door jamb having a horizontally disposed U-shaped portion forming a well therein, a detachable framework, and self-locking means secured to the framework and cooperating with the bottom of the U-shaped portion to retain the framework in said well when the framework is swung downwardly about said well, said framework being removable by swinging it upwardly about the well.

3. In a switchgear housing structure, in combination, a door jamb on the housing, said door jamb having a horizontally disposed U-shaped portion forming a well across the top and a vertically disposed well in each side, a detachable framework having a cross member insertable in the horizontal well to engage one leg of the U-shaped portion and brace members insertable in the vertical wells, and self-locking means cooperating with the bottom of the U-shaped portion to retain said members in said wells.

4. In a switchgear housing structure, in combination, a door jamb on the housing, said door jamb having a horizontally disposed U-shaped portion forming a well across the top and a vertically disposed well in each side, a detachable framework having a cross member insertable in the horizontal well to engage one leg of the U-shaped portion and brace members insertable in the vertical wells, and self-locking means secured to said cross member and cooperating with the bottom of the U-shaped portion to retain said members in said wells.

5. In a switchgear housing structure, in com-

bination, a door jamb on the housing, said door jamb having a horizontally disposed U-shaped portion forming a well therein, a detachable framework having a cross member insertable in said well to engage one leg of the U-shaped portion, and self-locking means secured to said cross member and cooperating with the bottom of the U-shaped portion to retain said member in said well when said cross member is rotated in one direction in said well by swinging the framework downwardly.

6. In a switchgear housing structure, in combination, a door jamb on the housing, said door jamb having a horizontally disposed U-shaped portion forming a well therein, a detachable framework having a cross member insertable in said well to engage one leg of the U-shaped portion, and self-locking means secured to said cross member and cooperating with the bottom of the U-shaped portion to retain said member in said well when said cross member is rotated in one direction in said well by swinging the framework downwardly, said locking means being released by swinging the framework upwardly to rotate the cross member in the other direction.

7. In a switchgear housing structure, in combination, a door jamb on the housing, said door jamb having a horizontally disposed U-shaped portion forming a well therein, a detachable framework having a cross member insertable in said well to engage one leg of the U-shaped portion, and self-locking means secured to said cross member and cooperating with the bottom of the U-shaped portion to retain said member in said well when said cross member is rotated in one direction in said well by swinging the framework downwardly, said framework being removable by swinging it upwardly to rotate the cross member in the other direction.
